UNITED STATES PATENT OFFICE.

GOTTFRIED JERLING, OF GARY, INDIANA, ASSIGNOR OF ONE-HALF TO FREDERICK E. HUMMEL, OF CHICAGO, ILLINOIS.

LOCK.

Application filed January 25, 1922. Serial No. 531,783.

To all whom it may concern:

Be it known that I, GOTTFRIED JERLING, a subject of Austria, residing at Gary, in the county of Lake and State of Indiana, 5 have invented new and useful Improvements in Locks, of which the following is a specification.

This invention relates to locks employing a main key-operated bolt and a latch-bolt 10 which is operated by a knob-spindle.

The invention has for its object to provide a novel and improved construction and arrangement of tumblers for the main bolt whereby the picking of the lock is rendered 15 extremely difficult and practically impossible.

The invention also has for its object to provide an arrangement of tumblers and an actuator for the main bolt, whereby the 20 same are operated by a longitudinal movement of a key, and without any turning movement thereof.

A further object of the invention is to provide a lock in which the turning of the 25 inside knob retracts both bolts.

Various other objects and advantages of the invention will be pointed out in the detailed description appearing hereinafter, and in order that the same may be better 30 understood, reference is had to the accompanying drawings forming a part of this specification.

In the drawings, Figure 1 is an elevation of the lock showing both bolts advanced; 35 Fig. 2 is a similar view showing the main bolt retracted; Fig. 3 is an elevation showing both bolts retracted; Fig. 4 is a perspective view of a certain part which is carried by the knob-spindle; Fig. 5 is a cross-section of the lock as installed; Fig. 6 is an inverted plan view of a pair of tumblers, and Fig. 7 is a plan view of a knob-spindle locking means.

Referring specifically to the drawings, 40 45 50 55 60 65 70 75 80 85 90 95 100

10 denotes the main bolt of the lock and 11 the latch bolt. These two bolts and the tumblers and other parts associated therewith are mounted in a casing 12 adapted to be mortised into the edge of a door or other closure and secured in any approved manner. The inner and outer door knobs are shown at 14 and 15, respectively, and the

spindle thereof at 16, the latter passing through the door and the lock casing.

The bolt 10 is operated by a lever 19 fulcrumed on a post 20 carried by the lock casing, the connection between said bolt and lever being made by a pin or stud 21 projecting from the former and seating in a slot 22 in the latter adjacent to one end 60 thereof. The other end of the lever 19 has a shoulder 23, the function of which will be presently described.

On a post 24 in the lock casing are pivoted superposed tumblers 25 and 26, and 65 an actuator lever 27 for the bolt 10, the same being located so that their free ends are beneath the lever 19. On the under side of the lever are two longitudinally spaced lugs 28 and 29 between which the free ends of the 70 tumblers 25 and 26, and the lever 27 are located.

The lever 27 is above the tumblers and passes close to the bottom lug 28, and when 75 it is swung in a counter-clockwise direction, it swings lever 19 in a direction to retract the bolt 10, it being understood, of course, that the lever must first be released, it being locked by the tumblers 25 and 26. In

order that the tumblers may lock the lever, 80 their free ends have ratchet edges, the ratchet teeth of the tumbler 25 being shown at 25^a and those of tumbler 26 at 26^a. The two tumblers are held spread by a spring 30 so that the ratchet teeth 25^a engage the 85 lower lug 28, and the ratchet teeth 26^a the upper lug 29. The spring 30 tends to swing the tumbler 25 downwardly to keep the teeth 25^a of its bottom edge in engagement with the lug 28, whereas the tumbler 26 is 90 forced upwardly by the spring to keep the teeth 26^a of its top edge in engagement with the lug 29. The spring 30 is coiled around the post 24 and has one free end pressing against a pin 31 depending from the under 95 side of tumbler 25, whereas the other free end of the spring presses against a pin 32 depending from the tumbler 26. From the outer face of the lever 27, extends a pin 33 against which presses a spring 34 anchored on post 24, said spring tending to oppose the swing of the lever 27 in a direction to effect retraction of the bolt 10. The spring 34 also operates to advance the bolt 10 by

pressing the lever 27 against the upper lug 29 of the lever 19. From the under side of tumbler 25 also depends a pin 35 having a function to be presently described.

5 The lever 27 and the tumblers 25 and 26 are operable by a key insertable from the outside of the door. This key, shown at 36, does not operate the lever and the tumblers by a turning movement, but swings the same by being pushed through apertures therein. The aperture of the lever 27 is shown at 27^b, that of tumbler 25 at 25^b, and that of tumbler 26 at 26^b. The lever 27, which operates the bolt actuating lever 19, must 10 be swung downwardly for retracting the bolt 10, whereas to effect the release of said lever 19, the tumbler 26 must be swung downwardly and the tumbler 25 upwardly. Figure 3 shows the tumblers in released position. The apertures 25^b, 26^b and 27^b are not in perfect alinement but are somewhat staggered with respect to each other, and hence when the key 36 is pushed into the apertures it tends to bring the latter into 15 alinement, so that the pressure of the key against the edges of the apertures causes the lever and the tumblers to swing in the proper direction to effect the release of lever 19 and the retraction of the bolt 10. In the aperture 27^b of the lever 27 is a barrier 27^c to prevent insertion of a false key. The key 36 will therefore have to be slotted in the direction of its length, as shown at 36^a in Figure 5, to clear the barrier. It will be 20 noted that the forward end of the key 36 is pointed so that it may enter the restricted opening formed by the partly alined apertures 25^b, 26^b and 27^b, and as the key is pushed forwardly, its wider portion, by a wedging action, causes the tumblers 25 and 26, and the lever 27 to swing as described.

25 The tumblers 25 and 26 are provided with a plurality of ratchet teeth 25^a and 26^a in order to augment the protection. Thus if the tumblers were jimmied to jerk over sufficiently to allow lever 19 to recede past one tooth, the next tooth would stop further movement of said lever. It will also be noted that the ratchet teeth are on both or 30 opposite edges of the tumblers, so that if an intruder should succeed in swinging the tumblers to assume a crossed relation, the teeth on the reverse edges would engage the lugs 28 and 29 to lock the lever 19.

35 The bolt 10 is also adapted to be held in retracted position by a pivoted detent 37 having one end adapted to engage the lug 29, and the other end of the detent being engageable by a pivoted cam member or tripper 38. The detent 37 is pivoted on a stud 39, and the cam member 38 is pivoted on a stud 40, these two studs being carried by the lock-easing. Cam member 38 has a forward extension 38^a and a curved tail section 38^b. Both the detent 37 and the cam

member 38 are fitted with springs 37^a and 38^c, respectively, exerting pressure in a clockwise direction, the spring 37^a being, however, more powerful than the spring 38^c.

40 The lock is also provided with the usual trigger 41 for holding the bolt 10 in retracted position.

45 The knob spindle 16 is fitted with a collar 42 which turns with the spindle and has radially projecting fingers 43 and 44, and a recess 45 in its inner end. Behind the collar 42 is a sleeve 46 having a radially extending finger 47, which seats in the recess 45. The collar and sleeve are in axial alinement, and are adapted to receive the 50 spindle 16, so as to turn with the latter when either door knob is operated. The collar is bored square, as shown at 48, to remain fixed on the spindle, while the sleeve, being intended to have a small amount of 55 relative motion or play for a purpose to appear later, is bored round and made to extend through the adjacent walls of the lock and door, so as to have fitted to it the inner knob 14. Between the knob and the 60 door, the sleeve 46 is cut with a transverse slot 49 through which the usual screw-stud 50 is passed into the spindle, securing the sleeve and spindle against relative movement in the direction of their length. The 65 slot 49 permits relative rotary motion, however, to provide a small amount of play between the knob 14 and the spindle, as suggested above.

70 The finger 44 extends into a recess 11^b in latch bolt 11 for retracting the same, and a spring 50 anchored to a post 51 is provided for advancing said bolt. Finger 43 is adapted to engage the tail section 38^b of cam member 38 to swing the same against the tension 75 of its spring 38^c. The spring 37^a presses against detent 37, as mentioned, to swing the same in a direction to engage lug 29 for locking the lever 19. The finger 43 is wide, being thus adapted to also engage the shoulder 23 of lever 19 to swing said lever in a 80 direction to retract the bolt 10.

85 The finger 47 is adapted to engage and rock a lever 54 fulcrumed on the post 51 and having a pointed or wedgeshaped end 54^a seating between the pin 35 of tumbler 25 and the pin 32 of tumbler 26, so that when the wedge is advanced, said tumblers are 90 swung to release the lever 19.

95 Figure 1 shows the position of the various parts when the door 13 is locked, the bolts 10 and 11 being both advanced. Upon inserting the proper key 36, the tumblers 25 and 26 are swung to release the lever 19, and the lever 27 swings in a direction to press down on the lug 28, with the result that the lever 19 is swung in a direction to 100 retract the bolt 10 against the tension of the spring 34. The detent 37, which of its tension bears on the lug 29 as the latter 105

recedes; now swings to engage the same, thereby locking the lever 19 to hold the bolt 10 in retracted position. The latch bolt 11 is still in advanced position, and to retract the same, the outer knob 15 is turned in a clockwise direction, and as the collar 42 turns with the knob spindle 16, the finger 44 swings in a direction to retract the bolt 11 against the tension of the spring 50. As the collar starts to turn, its finger 43 engages the tail section 38^b of the cam 38 and rocks said cam in a direction to lower its forward extension 38^a clear of a shoulder 11^a on the latch bolt so as not to impede the rearward travel of said bolt. Figure 3 shows the cam 38 rocked as just described. The rocking of the cam 38 in the direction described has no effect on the detent 37, so that the bolt 10 is still held in retracted position. The door 13 can now be swung open, and upon releasing the knob 15, the latch bolt 11 is automatically advanced by its spring 50, so that the head of the latch bolt passes from its position upon the extension 38^a, permitting the cam member to make a partial return swing by force of its spring 38^c, to the position shown in Figure 2. Now, when the door is pushed closed and the bolt 11 engages the strike plate of the keeper, said bolt is forced back, so that its shoulder 11^a strikes the extension 38^a, causing the cam member to tilt a further distance and press with its frontal edge against the back of the detent 37, thereby rocking said detent from the position in which it holds the bolt 10 retracted, as shown in Fig. 2, to the position shown in Fig. 1, in which latter position it has slipped off the lug 29, and as the lever 19 is now released, the bolt 10 is advanced automatically by the spring-actuated lever 27 into its keeper on the door jamb, the door 13 being now closed.

To open the door 13 from the inside, the knob 14 is turned, which, through finger 44 retracts the latch bolt 11. The motion of the knob sleeve 46 is not immediately transmitted to the spindle 16, due to presence of the transverse slot 49, which permits the sleeve to turn a short distance before engaging the screw stud 50 of the spindle. The collar 42 is also not affected by the initial motion of the knob sleeve, due to the length of the recess 45 relative to the width of the finger 47. The lost motion thus produced permits the said finger 47 to bear on lever 54 and swing the same in a direction to force its wedge-shaped end 54^a forwardly between the pins 32 and 35 of the tumblers 26 and 25, whereby said tumblers are swung to take their ratchet ends clear of the lugs 28 and 29 and thus leave the lever 19 free. Upon continuing to turn the knob 14, the finger 43 presses against the shoulder 23 of lever 19 and swings said lever in a direction to draw the bolt 10 back.

Figure 7 shows a slight modification which makes it impossible to turn the outer knob 15 to retract latch bolt 11 unless the main bolt 10 is fully retracted, thus making the latch bolt act as a locking bolt until the main bolt is fully retracted. To accomplish this, the bolt 10 has a shoulder 10^a engaging the end of a lever 55 provided at its other end with a hook 55^a, and intermediate its ends, with a shoulder 55^b. The lever 55 is held pressed against the bolt shoulder 10^a by a spring 56, and hence it swings when the bolt 10 advances. When the bolt 10 begins to advance, the lever 55 swings to engage its hook 55^a with the finger 43, and hence the knob spindle 16 is now locked, and it cannot be turned until the bolt 10 is retracted almost fully and swings the lever 55 in a direction to take the hook 55^a clear of the finger 43. The latter being part of the collar 42, and the collar being fixed on the spindle, it will be obvious that the outer knob cannot be turned. The case differs as to the inner knob, for a partial turn of the same will be sufficient to cause finger 45 to bear against lever 54 as previously described, and direct an extension 57 of said lever to engage shoulder 55^b of lever 55, so as to cause the latter to swing in a direction to take its hook 55^a clear of the finger 43, so that the knob spindle 16 is now fully released. The lever 55 is positioned behind the cam 38, the finger 43 being high enough to operate both of said parts.

In order that the sleeve 46 may not impede the removal of the lock from the door in the usual manner, the lock wall and door stock opposite the knob 14 are cut with a slot 58 communicating with the sleeve opening, to furnish an exit passage for the sleeve finger 47 as the sleeve is drawn out.

I claim:

1. In a lock, the combination with a bolt, of a plurality of tumblers therefor having apertures which are staggered and in partial alinement to form a restricted opening when the tumblers are in bolt-holding position, a key having a width greater than that of the opening the insertion of which into the opening moves the tumblers in opposite directions, such movement of the tumblers effecting the release of the bolt, and means acted upon by movement of said key in the direction of its length for retracting said bolt.

2. In a lock, the combination with a bolt, of a plurality of tumblers therefor having apertures which are staggered and in partial alinement to form a restricted opening when the tumblers are in bolt-holding position, a key having such a width that when inserted into the opening it engages one edge of the aperture of one tumbler and the opposite edge of the aperture of the other

tumbler for shifting the tumblers, such movement of the tumblers effecting the release of the bolt, and means acted upon by movement of said key in the direction of its 5 length for retracting said bolt.

3. In a lock, the combination with a bolt, of tumblers therefor, a bolt-retractor, said tumblers and the retractor having apertures which are staggered and in partial alinement to form a restricted opening, and a key 10 having a width greater than that of the opening for moving the tumblers and the retractor to release and to retract the bolt when said key is inserted into the opening.

15. 4. In a lock, the combination with a bolt, of tumblers therefor, a bolt-retractor, said tumblers and the retractor having apertures which are staggered and in partial alinement to form a restricted opening, and a key 20 having such a width that when it is inserted into the opening it engages opposite edges of the respective tumbler apertures and one edge of the retractor aperture, for shifting the tumblers and the retractor to 25 effect the release and the retraction of the bolt.

5. In a lock, the combination with a bolt, of a lever having an operative connection with the bolt, tumblers for locking the lever, 30 an actuator for the lever, and a key for operating the tumblers and the actuator, said key, the tumblers and the actuator having cooperating parts whereby the movement of the key solely in the direction of its length 35 operates the tumblers and the actuator.

40. 6. In a lock, the combination with a bolt, of a lever having an operative connection with the bolt, tumblers for locking the lever, said tumblers having ratchet teeth and the lever having lugs engageable by the ratchet teeth, an actuator for the lever, and a key 45 for operating the tumblers and the actuator, said key, the tumblers and the actuator having cooperating parts whereby the movement of the key solely in the direction of its length 50 operates the tumblers and the actuator.

7. In a lock, the combination with a bolt, of a lever having an operative connection 50 with the bolt, tumblers for locking the lever, said tumblers having ratchet teeth and the lever having lugs engageable by the ratchet teeth, an actuator for the lever, said actuator and the tumblers having key-receiving 55 apertures which are staggered and in partial alinement to form a restricted opening, and a key having a width greater than that of the opening for moving the tumblers and the actuator to effect the release and the 60 actuation of the lever.

8. In a lock, the combination with a bolt, of a lever having an operative connection with the bolt, tumblers for locking the lever, said tumblers having ratchet teeth and the 65 lever having lugs engageable by the ratchet

teeth, an actuator for the lever, said actuator and the tumblers having key-receiving apertures which are staggered and in partial alinement to form a restricted opening, and a key having such a width that 70 when it is inserted into the opening it engages opposite edges of the respective tumbler apertures and one edge of the actuator aperture, for shifting the tumblers and the actuator to effect the release and the actuation 75 of the lever.

9. In a lock, the combination with a bolt, of a lever having an operative connection therewith, tumblers for locking the lever, each tumbler having ratchet teeth on opposite edges, and the lever having a lug engageable by one of the toothed edges of one of the tumblers, and another lug engageable by one of the toothed edges of the other tumblers for locking the lever, the other toothed edges being engageable with the lugs upon an abnormal movement of the tumblers, and operating means for the tumblers. 80 85

10. In a lock, the combination with a bolt, of a lever having an operative connection therewith, tumblers for locking the lever, each tumbler having ratchet teeth, and the lever having lugs engageable by said ratchet teeth, and a key for operating the tumblers, said key and the tumblers having cooperating parts whereby the movement of the key solely in the direction of its length moves the tumblers in a direction to disengage 90 their ratchet teeth from the lugs. 95 100

11. In a lock, the combination with a bolt, of a lever having an operative connection therewith, tumblers for locking the lever, each tumbler having ratchet teeth, and the lever having lugs engageable by said ratchet teeth, an actuator for the lever, and a key for operating the tumblers and the actuator, said key, the tumbler and the actuator having cooperating parts whereby the movement of the key solely in the direction of its length moves the tumblers in a direction to disengage 105 their ratchet teeth from the lugs and operates the actuator. 110 115

12. In a lock, the combination with a bolt, of a lever having an operative connection therewith, tumblers for locking the lever, each tumbler having ratchet teeth, and the lever having lugs engageable by said ratchet teeth, an actuator for the lever, said actuator and the tumblers having apertures which are staggered and in partial alinement to form a restricted key-receiving opening, and a key having a width greater than that of the opening for moving the tumblers in a direction to disengage their ratchet teeth 120 from the lugs and to operate the actuator. 125

13. In a lock, the combination with a bolt, of a lever having an operative connection therewith, tumblers for locking the lever, each tumbler having ratchet teeth, and the 130

- lever having lugs engageable by said ratchet teeth, an actuator for the lever, said actuator and the tumblers having apertures which are staggered and in partial alinement to form 5 a restricted key-receiving opening, and a key having such a width that when it is inserted in the opening it engages opposite edges of the respective tumbler apertures and one edge of the actuator for shifting 10 the tumblers to disengage their ratchet teeth from the lugs and to operate the actuator.
14. In a lock, a main bolt, a knob-controlled latch bolt, and means independent of said latch bolt and controlled by the main 15 bolt for locking the knob.
15. In a lock, a main bolt, a latch bolt, a knob spindle having means for operating the latch, and a lever having means independent of said latch bolt for locking the 20 main bolt for actuation thereby to release the knob spindle when the main bolt is retracted.
16. In a lock, a main bolt, a latch bolt, a 25 knob spindle having means for operating the latch and carrying a projecting finger, and a lever engageable with said finger for locking the knob spindle, said lever being in the path of the main bolt for actuation 30 thereby to release the knob spindle when the main bolt is retracted.
17. In a lock, a main bolt, tumblers for 35 said bolt, a latch bolt, a knob spindle having means for operating the latch, a lever having means for locking the knob spindle, said lever being in the path of the main bolt for actuation thereby to release the knob spindle when the main bolt is retracted, tumblers for the main bolt, a releaser for said tumblers, and means carried by the knob spindle for operating the releaser, said releaser also having means for swinging the aforesaid lever to spindle-releasing position.
- 40 45 18. In a lock, a main bolt, tumblers for
- said bolt, a latch bolt, a knob spindle having means for operating the latch, a lever having means for locking the knob spindle, tumblers for the main bolt, a releaser for said tumblers, and means carried by the 50 knob spindle for operating the releaser, said releaser also having means for swinging the aforesaid lever to spindle-releasing position.
19. In a lock, a main bolt, a latch bolt, 55 operating means for the main bolt including a swinging member operatively connected to said bolt, a detent engageable with said member when the main bolt is in retracted position to hold the bolt in such position, and means controlled by the latch bolt for tripping the detent, said means being operable when the latch bolt is forced back as the part to which the lock is applied reaches its closed position.
20. In a lock, a main bolt, operating 60 means for said bolt including a swinging member operatively connected thereto, a detent engageable with said member when the main bolt is in retracted position to 70 hold said bolt in such position, a latch bolt, a knob spindle having an operative connection with the latch bolt, a tripper for the detent operable by the latch bolt when the same is forced back as the part to which the 75 lock is applied reaches its closed position, and means carried by the knob spindle for moving the tripper to inoperative position.
21. In a lock, a main bolt, a lever having 80 an operative connection therewith, tumblers for locking the lever, an actuator for the lever, said tumblers and actuator being key-operated, a latch-bolt, a knob-spindle having an operative connection with the latch bolt, means operated by the knob spindle 85 for actuating the lever, and means operated by the knob spindle for operating the tumblers.

In testimony whereof I affix my signature.
GOTTFRIED JERLING.
